UNITED STATES PATENT OFFICE.

ELMER E. HIGGINS, OF ST. PAUL, AND HARRY L. MCCOY, OF MINNEAPOLIS, MINNESOTA.

COLANDER.

No. 881,924.

Specification of Letters Patent. Patented March 17, 1908.

Application filed March 13, 1907. Serial No. 362,202.

To all whom it may concern:

Be it known that we, ELMER E. HIGGINS and HARRY L. MCCOY, citizens of the United States, residing, respectively, at St. Paul and 5 Minneapolis, in the counties of Ramsey and Hennepin and State of Minnesota, have invented certain new and useful Improvements in Colanders; and we do hereby declare the following to be a full, clear, and exact description of the invention, such as will enable others skilled in the art to which it appertains to make and use the same.

Our invention has for its especial object to provide an improved colander, and to this 15 end it consists of the novel devices and combinations of devices hereinafter described and defined in the claims.

In the accompanying drawings which illustrate the invention, like characters indicate 20 like parts throughout the several views.

Referring to the drawings, Figure 1 is a plan view of the improved colander. Fig. 2 is a section taken through the colander on the line $x^2 x^2$ of Fig. 1; and Fig. 3 is a detail view in plan of a device which acts as a combination scraper, lock and spring.

The bowl 1 of the colander in vertical cross section is preferably semi-cylindrical, and the bottom thereof is provided with a 30 multiplicity of small perforations indicated at 1^a. At one side, the bowl is rigidly secured to the end of a suitable hand-piece 2, and at its opposite side it is shown as provided with a pair of crooked supporting 35 fingers 3 that are adapted to be applied to the rim of a pan, jar or other receptacle. Working rotatively within the bowl 1 is a spiral feed blade 4, the convolutions of which extend from a point at the axis of the bowl 1 40 and increase in radius toward the top of the bowl. The extreme lower portion of the said feed blade is pivotally connected to the lower or bottom portion of the bowl 1 by a headed pin or stud 5 that depends through 45 the said bowl. At its upper end, the feed blade 4 is provided with a finger-piece 6 located eccentric to the common axis of the bowl, the feed blade and the pivot pin 5, so that the said feed blade may be radially rotated on said pivot pin. The lower portion 50 of the feed blade 4 closely engages at one edge with the perforated bottom portion of the bowl.

The numeral 7 indicates a piece of spring 55 wire which is bent upon itself to form a bowed segmental body portion 7^a and a fin-

ger portion 7^b. Furthermore, the body portion 7^a, at its central portion, is bent laterally to form a spring crotch 7^c, which spring crotch is, in turn, bulged at 7^d to afford a pin seat. The finger portion 7^b is passed through a perforation in the depending end of the pivot pin 5. Then the bowed body portion 7^a is moved upward by a lateral pivotal motion and the bulges 7^d of the spring 60 crotch 7^c are caused to engage the pin 5 adjacent to the bottom of the bowl 1. When the said spring device is thus applied as shown in Fig. 2, its bowed body portion presses frictionally against and closely engages the perforated bottom portion 1^a of the 65 bolt, and under rotation of the feed blade 4 will act as a scraper to scrape from the bottom of the bowl any material that has been forced through the perforations thereof. 70 The pivot pin 5 should be soldered, riveted or otherwise rigidly secured to the lower end of the feed blade 4. The said spring device when thus applied also serves to yieldingly draw the lower portion of the feed blade 75 against the perforated bottom of the bowl, and it also serves to lock the said feed blade 80 against the working position within the bowl.

The use of a device of this kind is well understood. The material to be worked 85 through the colander is dropped into the bowl 1 and under rotation of the spiral feed blade 4 it will be fed or pressed downward against the bottom of the bowl, and upon reaching the bottom of the bowl will be 90 forced through the perforations thereof under the pressing scraping action of the feed blade. The feed blade has considerable elasticity, so that it will adapt itself to the material within the bowl, but the lower portion 95 of the said feed blade will always be held in close engagement with the perforated bottom of the bowl 1. It is important to note that the spiral blade is so formed that there is an axial opening left in the upper portion 100 thereof through which the material to be pressed through the perforated bowl may be fed into the bowl and under the spiral blade.

In practice, the improved colander above described has been found highly efficient for 105 the purposes had in view. The device while especially designed for use as a colander is, nevertheless, capable of use as a sifter for flour and other finely ground material.

What we claim is:

1. In a colander, the combination with a bowl having a perforated bottom, of a ta-

pered spiral feed blade, the lower portion of which closely fits and is arranged to scrape over the perforated bottom of said bowl, and the upper portion of which is left with an axial opening for the free feed of material into the bowl and is provided with means for rotating said feed blade within said bowl, substantially as described.

2. In a colander, the combination with a bowl having a perforated bottom, of a spiral feed blade rotatively mounted in said bowl and pivotally connected at its lower end to the bottom thereof, and a scraper mounted to rotate with said feed blade and to press against the lower surface of the perforated bottom of the bowl, substantially as described.

3. In a colander, the combination with a bowl having a perforated bottom, of a spiral feed blade rotatively mounted therein and pivotally connected at its lower end to the bottom thereof, and a combined spring and scraper arranged to rotate with said feed blade, to pass over the under surface of the perforated bottom of the bowl, and to yieldingly draw the lower end portion of said feed blade against the upper surface of the perforated bottom of the bowl, substantially as described.

4. In a colander, the combination with a bowl having a perforated bottom, and a handle, of a spiral feed blade rotatively mounted in said bowl, pivotally connected at its lower end to the perforated bottom thereof in line with the common axis of said bowl

and spiral feed blade, said spiral feed blade having a finger piece at its upper end located eccentric to the axis of said feed blade and bowl, and a spring pressed scraper mounted to rotate with said feed blade and to pass over the under surface of the perforated bottom of the bowl, substantially as described.

5. In a colander, the combination with a bowl having a perforated bottom, of a spiral feed blade rotatively mounted in said bowl and provided at its upper end with a finger piece located eccentric to the common axis of the bowl and feed blade, a pin or stud secured to the lower end of said feed blade and depending through the perforated bottom of the bowl, and a combined scraper, lock and spring device constructed from a piece of spring wire bent upon itself to form the bowed scraper portion 7^a, spring finger 7^b and crotch 7^c with bulged portion 7^d, the said finger portion 7^b being insertible through a perforation in the depending end of said pin 5, the bulged crotch portion 7^d being engageable with the body of said pin, and the said scraper portion 7^a being engageable with the under surface of the perforated bottom of the bowl, substantially as described.

In testimony whereof we affix our signatures in presence of two witnesses.

ELMER E. HIGGINS.
HARRY L. MCCOY.
